UNITED STATES PATENT OFFICE.

EDWARD C. EWER AND WILLIAM G. WALDRON, OF LANSING, MICHIGAN.

ROOF FLASHING.

Application filed October 26, 1928. Serial No. 315,188.

This invention relates to roof flashings, intended to protect any built up, prepared or metal roof from water or dampness getting between the edges and sidewall of the building or under the roofing.

The object of this invention is to provide a flashing construction of such simple construction that it may be fully understood by simple inspection equally as to its formation and the method of its application. It is similarly an object to produce such a device which may be located at various portions of the meeting places of all roofs and brick, tile or concrete walls, and which may be made permanently leak proof, and which will not be displaced by alternate expansion and contraction due to changes in temperature.

This invention consists in the special design and combination of parts as illustrated in the accompanying drawings, of which Fig. 1 represents a flashing made in accordance with this invention and applied to the turned up edge portion of a roof, upon which is the roof flashing, showing the holding part passed through the roof flashing, thus eliminating all nailing of roof flashings. Fig. 2 illustrates the parts as set forth in Fig. 1, and shows the bent outer member in position, but the lip member has not been turned down. Fig. 3 shows the parts of this invention made in one piece, ready to be applied to a roof, representing the lip before bending, and the holding part before being clamped in final position. Fig. 4 shows a section of a brick wall and roof with this invention applied thereto, and exhibits all parts in place.

Throughout the drawings and description, the same number is used to refer to the same part.

Considering the drawings, the metal flashing 1 has an upturned edge portion on the top of which is placed the flashing constituting this invention and comprising a flat body portion 2 arranged horizontally, and having an angularly disposed edge portion 3. The body is formed into an S-shaped portion 4 located above the body, and the upper fold of the S-shaped portion is extended in a bendable lip 5.

A part of the body 2 is stamped out and bent downwardly and at right angles for a threefold purpose, to produce the opening 6 which allows the mortar to pass through, thus cementing the metal in place; the downwardly bent portion to form a guide for aligning the metal when laid in the wall; to

form the holding part 7 as it is intended to pass the right angle end portion of the holding part through the upturned edge portion of the roof flashing 1 as illustrated in Fig. 1. After being passed through the roof flashing the end of the guide or holding part 7 is clinched upon the roof flashing as set out in Fig. 4, thus holding the roof flashing in place and eliminating the necessity of nailing. Opening 6 shows the shape of part 7.

To complete this invention, an outer member 8 is provided, having a portion bent at a right angle and inserted in the upper fold of the S-shaped portion of the body mentioned. The vertical portion of the outer member 8 will now cover the clinched engagement of the guide member and the roof flashing, and as customarily formed the outer member has its lower edge portion bent somewhat to contact with the roof flashing exteriorly as best shown in Fig. 4.

It is not intended to confine this invention to any particular metal or material, or to the size of the several formations devised to make up the whole.

In the operation of this invention, as will be best understood from Fig. 4, it is assumed to have been applied to the wall of a building constructed by bricks 10 with mortar between them marked 11.

The body 2 is embedded in the mortar 11, and the angularly projecting edge portion 3 of the body acts to retain the body against displacement in the mortar. The guide or holding part 7 is passed through the edge portion of the roof flashing and clinched thereupon as illustrated. The outer member is placed in the upper fold of the S-shaped portion 4 and the parts closed together securely on the bent portion of the outer member, while the lip 5 is turned downwardly against the member 8 externally. This brings the lower edge of the outer member against the roof flashing. It is believed to be now apparent that no water can leak in over the edge of the roof flashing, as it is covered by the continuous portions of this body, and no water can blow in between the lower bent edge of the outer member and the roof flashing, and the stated and desired object of this invention is attained.

Having now described this invention, and explained the manner of its use, we claim:

1. In roof flashing, the combination with a roof, of flashing comprising a flat body portion arranged horizontally, an S-shaped fold-

ed portion located above the said body portion, a lip extending from the upper fold of the S-shaped portion, a bendable holding part connected with the said body portion and adapted to be passed through the edge portion of the roof flashing, and a bent outer member having one portion engaging the said S-shaped fold and the other portion arranged over the said engagement of the holding part 5 of the roof flashing, the said lip being turned up over the said outer member to additionally hold the same in place.

2. In roof flashing, the combination with a roof, of flashing comprising a flat body portion arranged horizontally, and S-shaped folded portion located above the said body portion, a holding part formed integrally with the said body portion and adapted to be passed through the edge portion of the roof 15 flashing, and a bent outer member engaging the said S-shaped portion, the said lip being turned down over the outer member to additionally hold the same in place.

3. In roof flashing, the combination with a roof, of flashing comprising a flat body portion arranged horizontally, an S-shaped folded portion located above the said body por- 25

tion, a holding part formed integrally with the said body portion to form an opening for the mortar to pass through and cement the 30 body portion in place and adapted to be passed through the edge portion of the roof flashing, and a bent outer member engaging the said S-shaped portion, the said lip being turned down over the outer member to additionally 35 hold the same in place.

4. In roof flashing, the combination with a roof, of flashing comprising a flat body portion arranged horizontally, an S-shaped folded portion located above the said body portion, guides formed integrally with the said body portion to aid in aligning the body portion to the roof, a holding part formed from the said guide members and adapted to be passed through the edge portion of the 40 roof flashing, and a bent outer member engaging the said S-shaped portion, the said lip being turned down over the outer member to additionally hold the same in place.

In testimony whereof we affix our signatures.

EDWARD C. EWER.
WILLIAM G. WALDRON.
